(57) CLAIM

The ornamental design for a sports bag, as shown and described.

DESCRIPTION

1. Sports bag
- 1.1 : Perspective
- 1.2 : Front
- 1.3 : Back
- 1.4 : Right
- 1.5 : Left
- 1.6 : Top
- 1.7 : Bottom
- 1.8 : Perspective, shown in an alternate position
- 1.9 : Perspective, shown in another alternate position
- 1.10 : Perspective, shown in another alternate position
- 1.11 : Perspective, shown in another alternate position
- 1.12 : Perspective, shown in another alternate position
